(57) **CLAIM**

The ornamental design for a splatter shield, as shown.

DESCRIPTION

FIG. 1 is a perspective view of a “splatter shield” incorporating the design of my invention;

FIG. 2 is a top plan view thereof;

FIG. 3 is a bottom plan view thereof;

FIG. 4 is a side view thereof;

FIG. 5 is the opposite side view thereof;

FIG. 6 is a front view thereof; and,

FIG. 7 is a rear view thereof.
